UNITED STATES PATENT OFFICE

95,477

DESIGN FOR A DRESS

Samuel Zahn, New York, N. Y.

Application April 1, 1935, Serial No. 56,173

Term of patent 3½ years

To all whom it may concern:

Be it known that I, Samuel Zahn, a citizen of the United States of America, residing in Manhattan, county of New York, and State of New York, have invented a new, original, and ornamental Design for a Dress, of which the following is a specification, reference being had to the accompanying drawing, forming part thereof, wherein,

The parallel lines on the front of the shoulders and across the back represent tucks.

The cuff-like portion on the lower extremities of the collar represent two hollow stitched pieces of self material sewed on to a flat collar and tied together with pipings of self material.

I claim:

The ornamental design for a dress, substantially as shown and described.

SAMUEL ZAHN.
